3 Sheets-Sheet 3

UNITED STATES PATENT OFFICE.

JOHN M. HOTHERSALL, OF BROOKLYN, NEW YORK, ASSIGNEE TO AMERICAN CAN COMPANY, OF NEW YORK, N. Y., A CORPORATION OF NEW JERSEY.

SHEET-GAUGING DEVICE FOR SLITTING MACHINES.

Application filed August 19, 1922. Serial No. 582,908.

To all whom it may concern:

Be it known that I, JOHN M. HOTHERSALL, a citizen of the United States, residing in Brooklyn, in the county of Kings and State of New York, have invented a new and useful Improvement in Sheet-Gauging Devices for Slitting Machines, of which the following is a specification.

My invention relates to slitting machines which are employed to cut sheet metal stock, for use in can bodies and the like, and has more particular reference to devices in a machine of this character for accurately gauging or squaring up the sheets preparatory to their being fed through the slitting elements.

A principal object of the invention is the provision of gauging devices for the purpose stated which are adapted to operate with the accuracy required in the feeding of decorated stock, such as lithographed sheets of tin plate, it being especially necessary to attain a high degree of accuracy in the handling of such sheets to prevent their surfaces being marred or damaged during the slitting operation.

It is another object of the invention to provide gauging members in a slitting machine which are adapted to engage the points on a lithographed sheet which have previously been the gauging points in a lithographing press, it being noted, in this connection, that the uniform method of positioning sheets in such a press is by means of a three-point system, in which the sheet is engaged at two gripper points in one edge and at a third point in another edge whereby it is positively and exactly located for printing.

A further object of the invention is the provision of slitter feed gauging devices which, after properly gauging and squaring up the sheet, hold it in accurate position as it moves into the slitting rollers, thus preventing slippage or relative movement which would result in damage to the surface condition, as well as cause misalignment of the sheet. The invention also contemplates, in this connection, the provision of means for retracting certain of the gauging members after the sheet has been accurately engaged by the cutting elements, in order to permit sheets of irregular formation to pass by without changing their line of travel as they move through said cutting elements.

Other objects and advantages of the invention will be apparent as it is better understood from the following description, which, taken in connection with the accompanying drawings, discloses a preferred embodiment thereof.

Referring to the drawings,

Figure 1 is a plan view of a slitting machine in which my invention is embodied;

Fig. 2 is a side elevation thereof;

Fig. 3 is a sectional view taken substantially on the line 3—3 in Fig. 1 and showing the front gauging finger;

Fig. 4 is a section taken substantially on the line 4—4 in Fig. 1 and showing in detail the means for moving the slide upon which the side gauging devices are mounted;

Fig. 5 is a partial section taken substantially on the line 5—5 in Fig. 1; and

Fig. 6 is a bottom plan view showing the table extension arm and being taken substantially on the section line 6—6 in Fig. 3.

The slitting machine shown upon the drawings, for the purpose of illustration, comprises a table 11, which is supported upon an upper frame 12 having bearing brackets 13 and 14 bolted thereto at opposite sides and in which the cutting elements are mounted, the entire mechanism being suitably supported upon a lower frame part 15. The sheets are fed across the table 11, in any approved manner, and are operated upon by means of slitting rollers 16 and 17, which are provided in any desired number upon upper and lower shafts 18 and 19, these shafts being mounted in adjustable bearing blocks 21 and 22 in the brackets 13 and 14. The cutting elements are operated by rotation of these shafts, the lower one being driven by means of a pulley 23 on the end thereof and being geared by means of gears 24 and 25 to the shaft 18.

Before a sheet enters the slitting rollers, it is necessary that it be suitably gauged to square up the front edge with respect thereto, so that it may be accurately operated upon by the cutting elements. For this purpose, I provide gauging devices which consist, in the present instance, of a front gauging finger 26 and side gauging levers 27 and 28, though it will be understood that two gauging points might be arranged at the front and one at the side, if desired. The finger 26 is secured by means illustrated in detail in Fig. 5 to a rock shaft 29, which is

mounted in ball bearings 81 in bracket arms 32 extending upwardly from the brackets 13 and 14.

A block cam 33 is secured upon the rock shaft 29 by means of a cap screw 34 and the upper end of the gauge finger is secured to said cam by means of a set screw 35 and clamping screws 36 and 37. Said finger is vertically adjustable in a slideway 38 in the front of the block 33, being provided with a suitable slot 39 (Fig. 5) to permit movement relative to the screw 35. Upon the lower end of the finger is a roller 41 which may be adjusted with respect to the top of the table 10 by the mechanism just described. An extension arm 42 is adjustably secured to the bottom of the table by bolts 43 and 44 extending through slots 45 and 46 (Fig. 6) and said arm serves to support the advancing sheet 15 adjacent the point where it is gauged by the finger 26.

An adjustable frame part and guide 47 is secured at the side of the table by a bolt and slot connection, as indicated at 48, and the inner side of said frame part is provided with a groove 49, which provides a slideway for a slide 51, the gauging levers 27 and 28 being pivotally secured at 52 and 53, respectively, to pivot members 54 and 55, which are secured by screws 56 and 57 to said slide. Said levers 27 and 28 have their engaging points normally urged outwardly by springs 58 and 59 and are held in gauging position by pins 61 and 62 bearing against cam members 63 and 64.

Referring now to Fig. 4, it will be noted that an arm 65 is connected by means of a link 66 with the front end of the side 51 and the upper end of said arm is rigidly mounted upon the rock shaft 29. Upon said shaft, there is also secured a forwardly extending arm 67, which is yieldingly connected by a spring 68 with the frame bracket 13. A set screw 69 is provided in the frame beneath said arm 67 and serves to adjustably limit the downward movement thereof.

In operation, a sheet is fed across the table 11 until its front edge comes in contact with the roller 41 on the gauge finger 26, it being retarded thereby and the side edges being forced against the gauging levers 27 and 28. In this manner, the sheet is accurately located and may safely be fed between the slitting rollers. The sheets, however, may be of irregular formation, as, for example, having the front edge of less width than the back, and it is obvious that continued movement of such a sheet after being gauged would result in deflecting the line of travel, if the side gauging devices were stationary. I, therefore, provide means for moving said side gauging devices with the sheet after the latter has been squared up until it is fully engaged by the slitting rollers. The means whereby this is accomplished is perhaps best

illustrated in Figs. 3 and 4. After a sheet has come in contact with the roller 41, the gauging finger 26 is moved thereby and serves to rock the shaft 29, which also carries the arm 65 which is secured to the forward end of the slide 51. It will be thus apparent that when the finger 26 is lifted by the force of the sheet to permit the latter to pass, the arm 65 is actuated to draw the slide 51 and therewith the gauging levers 27 and 28 in forward direction. The sheet is, in this manner, securely held at the points originally engaged until it has entered the slitting rollers. In the event that the sheet is of the irregular formation heretofore referred to, continued movement thereof through the rollers would yet tend to deflect the path of travel if the lateral position of the gauging levers 27 and 28 remained the same during said continued movement of the sheet. In other words, assuming that the back of the sheet is of greater width than the front, the projecting rear corner would act upon the gauging levers to twist the sheet and thus cause damage thereto in the slitting rolls. I, therefore, provide means for retracting said levers 27 and 28 after they have traveled with the sheet a predetermined distance. It will be observed, by an inspection of Fig. 1, that the cam members 63 and 64 are beveled at 71 and 72 to permit the pins 61 and 62 to ride outwardly thereon under the force of the springs 58 and 59. In this manner, the wide rear edge of a sheet of the character described may pass safely by without being obstructed, or the course of the sheet altered by the levers 27 and 28.

The distance which said gauging levers travel with the sheet before being retracted may be varied at will by adjustment of the cam members 63 and 64, the latter being adjustably secured by screws 73 and 74 in slots 75 and 76 provided in the upper part of the side frame part 47. The slide 51 is held in the groove 49 by means of screws 77 and 78 slidable in slots 79 and 81 in the lower part of the frame member 47. Since said member 47 may have its position upon the table 11 adjusted by the bolt and slot connection indicated by the reference character 48, it is manifest that the gauging devices may be positioned to accommodate sheets of different size and the action thereof may be controlled with extreme accuracy.

It is thought that the invention and many of its attendant advantages will be understood from the foregoing description and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. In a machine for slitting sheet metal and the like, the combination of slitting elements, a table upon which the sheets are fed to said elements, and gauging devices comprising front and rear side gauging levers for aligning the sheets upon said table, said devices being adapted to move a predetermined distance in holding engagement with a sheet and being thereafter retractable to permit passage of an irregular sheet portion. 70
- 5 2. In a machine for slitting sheet metal and the like, the combination of slitting elements, a table upon which the sheets are fed to said elements, and gauging devices comprising a member in the path of the sheets at the front of the table and means at the side of the table co-operating with said front member to align the sheets, said means being movable a predetermined distance in holding engagement with an advancing sheet. 80
- 10 3. In a machine for slitting sheet metal and the like, the combination of slitting elements, a table upon which the sheets are fed to said elements, and gauging devices comprising a member in the path of the sheets at the front of the table and means at the side of the table co-operating with said front member to align the sheets, said means being adjustable to move over variable distances in holding engagement with an advancing sheet. 85
- 15 4. In a machine for slitting sheet metal and the like, the combination of slitting elements, a table upon which the sheets are fed to said elements, and gauging devices comprising a member in the path of the sheets at the front of the table and means at the side of the table co-operating with said front member to align the sheets, said means being movable a predetermined distance in holding engagement with an advancing sheet and being thereafter retractable to prevent deflection of an irregularly formed sheet. 90
- 20 5. In a machine for slitting sheet metal and the like, the combination of slitting elements, a table upon which the sheets are fed to said elements, and gauging devices comprising a member in the path of the sheets at the front of the table and means at the side of the table co-operating with said front member to align the sheets, said means being movable in holding engagement with an advancing sheet until the latter is fully engaged by the slitting elements. 95
- 25 6. In a sheet metal slitting machine, the combination of cutting elements, a table upon which sheets are adapted to be moved to said cutting elements, three-point gauging devices adapted to engage and hold a sheet as it advances toward said cutting elements, a part of said devices being arranged at the side of the table and being yieldable at predetermined points to permit unobstructed movement of irregular sheets after they have been engaged by the cutting elements. 100
- 30 7. In a machine for slitting sheet metal and the like, the combination of slitting rolls, a support on which the sheets are fed to said rolls, yieldable side gauging means for gauging the sheet at two separated points, and a front gauge to temporarily arrest the sheet and cause it to bear against said side gauging means, said side gauging means being movable with the sheet until it has reached said rolls. 105
- 35 8. In a sheet metal slitting machine, the combination of cutters, a support upon which the sheets are fed to said cutters, and means on said support for accurately locating an advancing sheet and positively holding it in the desired path of travel, said means comprising a gauging finger in the path of the sheets and movable therewith and means adjacent and also movable along said path for engaging the sheet at certain points and maintaining said engagement during predetermined advancing movement. 110
- 40 9. In a sheet metal slitting machine, the combination of cutters, a support upon which the sheets are fed to said cutters, and means on said support for accurately locating an advancing sheet and positively holding it in the desired path of travel, said means comprising a gauging finger in the path of the sheets and means adjacent said path for engaging the sheet at certain points and maintaining said engagement during predetermined advancing movement, said means being then retractable to prevent deflection of an irregularly formed sheet. 115
- 45 10. In a sheet metal slitting machine, the combination of cutters, a support upon which the sheets are fed to said cutters, and means on said support for accurately locating an advancing sheet and positively holding it in the desired path of travel, said means comprising a gauging finger in the path of the sheets and means adjacent said path for engaging the sheet at certain points and maintaining said engagement during predetermined advancing movement, said means being then retractable to prevent deflection of an irregularly formed sheet. 120
- 50 11. In a sheet metal slitting machine, the combination of cutters, a support upon which the sheets are fed to said cutters, and means on said support for accurately locating an advancing sheet and positively holding it in the desired path of movement, said means comprising a liftable gauging finger in the path of the sheets, a rock shaft upon which said finger is mounted, means adjacent the path of travel of the sheets for engaging an advancing sheet, a slidable support for said means, and a member mounted on said rock shaft and connected with said support whereby action of a sheet upon said finger draws said support forward and maintains engagement of said means with the sheet during predetermined movement thereof. 125
- 55 12. In a sheet metal slitting machine, the combination of cutters, a support upon 130
- 60 65 70 75 80 85 90 95 100 105 110 115 120 125 130
7. In a sheet metal slitting machine, the

which the sheets are fed to said cutters, and means on said support for accurately locating an advancing sheet and positively holding it in the desired path of movement, 5 said means comprising a liftable gauging finger in the path of the sheets, a rock shaft upon which said finger is mounted, means adjacent the path of travel of the sheets for engaging an advancing sheet, a slidable support for said means, a member mounted on said rock shaft and connected with said support whereby action of a sheet upon said finger draws said support forward and maintains engagement of said means with the 10 sheet during predetermined movement thereof, and means causing retraction of said movable sheet-engaging means at a predetermined point.

13. In a sheet metal slitting machine, the 20 combination of slitting rollers, a support upon which the sheets are fed to said rollers, and devices for squaring the sheets on said support prior to their entry into said slitting rollers, said devices including a vertically adjustable gauging finger disposed in the path of the sheets and adapted to yieldingly resist the movement thereof.

14. In a machine for cutting lithographed sheets, the combination of cutting elements, 25 a support upon which the sheets are moved to said elements, and gauging devices for the side of the sheet spaced from each other and engaging the sheet at two points adapted to engage the points on the sheet by which

it was gauged in the lithographing press to 35 square up said sheets prior to their being subjected to the cutting elements, and a front gauging device, said gauging devices being movable with the sheet for a predetermined 40 distance.

15. In a machine for cutting lithographed sheets, the combination of cutting elements, a support upon which the sheets are moved to said elements, and gauging devices spaced apart one at the rear of the other and 45 adapted to engage the points on the sheet by which it was gauged in the lithographing press to square up said sheets prior to their being subjected to the cutting elements, certain of said gauging devices being movable 50 with a sheet at a side thereof until the sheet is engaged by said cutting elements to permit passage of irregular sheet portions without deflecting the path of travel.

16. A slitting machine having slitting 55 rolls, and means for engaging the edge of a lithographed sheet at two separated points to position the sheet accurately to be acted on by said rolls, the position of the sheet being unaffected by the other parts of the 60 edge by which it is positioned, whereby the sheet may be gauged in the slitting machine as it was in the printing machine and the slitting caused to accord accurately with the lithographing, said engaging means being 65 movable with the sheet until it reaches said rolls.

JOHN M. HOTHERSALL.
